UNITED STATES PATENT OFFICE

GERTRUDE NICKERSON, OF MILFORD, CONNECTICUT, ASSIGNOR TO KOPS BROTHERS, INC., OF NEW YORK, N. Y., A CORPORATION OF NEW YORK

GARMENT

Application filed September 4, 1931. Serial No. 561,127.

This invention relates to improvements in garments and more particularly in girdles, corset and combination garments. An important feature of the improved garment is the provision of a diaphragm supporting structure which will provide the desired support to the diaphragm at all times but is capable of yielding at the front of the garment in order to avoid discomfort while a person, particularly one inclined to be stout, is seated. To this end suitable elastic straps or bands are extended between the sides of the garment and a portion extending over the diaphragm at the front and these bands are so connected to the remaining portions of the garment as to provide a relatively free yielding structure toward the top of the diaphragm. In one embodiment of the invention the construction may be such that the garment is substantially unyielding toward the bottom of the diaphragm or at the waist line. In another embodiment provision is made for a certain amount of yielding at all portions of the diaphragm and at the waistline although the elasticity adjacent the top of the diaphragm is considerably greater than at other points.

Other objects and advantages of the invention will appear as the detailed description of an illustrative embodiment of the same proceeds in conjunction with the accompanying drawings, in which:

Figure 1 is a front elevational view of the garment as it would appear when encircling the body.

Figure 2 is a detailed sectional view along the line 2—2 of Figure 1 showing the upper edge of one of the elastic bands, and

Figure 3 is a view showing a portion of the inside of the garment opened out.

Referring now to the drawings, the garment may comprise any suitable form of girdle having portions of elastic material and other portions of inelastic material, the various portions being so arranged as to provide a

yielding structure which will conform readily to the contours of the body. This girdle structure may either form a continuous, unbroken band of the step-in type or it may be provided with suitable fasteners adapted to join the free ends along the line 9 at the side

of the wearer. At the front there may, for example, be provided a pair of inelastic sections 10 and 11 having joined thereto by lines of stitching 12 and 13 a pair of central sections 14 and 15. These are formed of inelastic material and are joined along the front center line of the garment by lines of stitching 16. As shown, the sections 14 and 15 are preferably tapered slightly from the bottom toward the top, being somewhat wider at the top. They extend a considerable distance above the sections 10 and 11 so that their upper portions overlie the diaphragm of the wearer. Sections 10 and 11 may terminate substantially at the waistline while the central portion formed by sections 14 and 15 will extend a considerable distance above the waistline. To provide a desirable yield at the lower end of the central section, a triangular insert 17 of elastic material is secured to the sections 14 and 15 by lines of stitching 18 and 19.

Above the sections 10 and 11 and secured thereto by lines of stitching 20 and 21 are small sections 22 and 23 of inelastic material. These small sections form anchor members for elastic bands 24 and 25. The band 24 is secured to the section 22 by lines of stitching 26 and to the section 14 by lines of stitching 27. Furthermore, this elastic member is secured along its lower edge 28 to the upper end of the section 10 by means of suitable stitching. In a similar way the elastic member 25 is secured to the anchor member 23 by stitching 29 and to section 16 by stitching 30 while its lower edge 31 is stitched to the top of the section 11. As shown in Figure 1, the members 24 and 25 are arranged diagonally downward to a slight degree from the outer edges thereof toward the sections 14 and 15 so that an uplift effect is had upon the upper ends of these sections which serve to support the diaphragm.

If the garment is to be a combination a suitable form of brassière may be attached to the upper edge of the girdle portion. For this purpose the brassière may be formed of two sections 32 and 33 of any suitable material, lace being employed if desired. These sections may be secured at the edges 34 and

35 of the front portion of the garment and may be joined at the center of the front by the lines of stitching 36 forming an extension of the stitching 16. Along its lower edge the 5 brassière may be anchored to the central sections 14 and 15 by stitching 37 and 38 and a portion of the stitching 16 but it will be left free of the elastic bands 24 and 25. The lower edge may also be stitched at 39 and 40 to 10 the upper edges of the anchor members 22 and 23. Suitable shoulder straps 41 and 42 may be provided for properly suspending the upper edge of the brassière.

On the inner side of the garment, as best 15 shown in Figure 3, there is provided an inelastic diaphragm band or pad 43 which is secured along the edges 44 and 45 to the edges of the front member of the garment. Stiffening members, such as stays 46, may be vertically disposed intermediate the ends of the pad. The pad is entirely free intermediate the edges 44 and 45 and is of such length as to permit a limited stretching of the bands 24 and 25 along their upper edges. Due to 20 the fact that these elastic bands are stitched along their lower edges to the inelastic material of the sections 10 and 11, they will not be permitted to stretch at this point to an appreciable extent. This provides for greater freedom 25 in the support of the diaphragm adjacent the upper portion thereof than toward the lower portion. Accordingly, when a stout person wearing the garment assumes a sitting posture the tendency of the flesh at the front of the wearer to rise will be permitted; with the result that the discomfort attending 30 too close confinement of the flesh adjacent the diaphragm will be avoided while the diaphragm is still held in its correct position.

35 40 While an illustrative form of the invention has been disclosed in considerable detail in the foregoing, it will be understood that various changes may be made in the form and arrangement of the various portions of the garment without departing from the spirit and scope of the invention as defined by the claims.

What I claim is:

- 50 1. A combination garment comprising a front, girdle member having a central portion extending above the waist-line, a brassière attached to the upper edge of said central portion, anchor members between said front member and said brassière and attached to both at the sides thereof, and a pair of elastic straps extending from said anchor members to the edges of said central portion, said straps being secured along their lower edges to said front member.
- 55 60 2. A combination garment comprising a front, girdle member having a central portion extending above the waist-line, a brassière attached to the upper edge of said central portion, anchor members between said front member and said brassière and attached

to both at the sides thereof, and a pair of elastic straps extending from said anchor members to the side edges of said central portion, said straps being secured along their lower edges to said front member and being extended diagonally upward from said central portion to provide an uplift effect upon the dia- 70 phragm.

3. A combination garment comprising a front, girdle member having a central portion extending above the waist-line, a brassière attached to the upper edge of said central portion, anchor members between said front member and said brassière and attached to both at the sides thereof, a pair of elastic straps extending from said anchor members to the side edges of said central portion, said straps being secured along their lower edges to said front member, and a diaphragm pad suspended freely at said anchor members and underlying said straps and central portion. 80

In testimony whereof, I have signed my name to this specification this 1st day of September, 1931.
